UNITED STATES PATENT OFFICE.

CHESTER R. PIEPER, OF LA CROSSE, WISCONSIN.

EARTH-ANCHOR.

1,250,350.

Specification of Letters Patent. Patented Dec. 18, 1917.

Application filed October 7, 1914. Serial No. 865,450.

To all whom it may concern:

Be it known that I, CHESTER R. PIEPER, a citizen of the United States, residing at La Crosse, in the county of La Crosse and 5 State of Wisconsin, have invented a certain new and useful Improvement in Earth-Anchors, of which the following is a full, clear, concise, and exact description, reference being had to the accompanying drawings, forming a part of this specification.

My invention, in one of its aspects, relates to that class of earth anchors that employ blade carrying shafts which are first to be driven into the ground approximately the 15 full distance they are to enter the ground, and are thereafter to be turned in order to cause the blades, that are initially folded to be with their earth penetrating ends uppermost and against the shafts, to spread 20 apart and enter the earth as the shafts are turned. Another features of the invention is, however, not to be limited to this particular type of earth anchor. The invention has two main objects; one being the 25 provision of an improved earth penetrating pilot at the lower end of the blade carrying shaft, and the other an improved formation of the upper end of an anchor shaft into a guy wire receiving eye of such shape that it 30 will not collapse or become distorted under the heavy blows of the sledge hammer employed to drive the anchor shaft into that position in which it is to be turned to force the blades into the ground.

35 The pilot or earth penetrating enlargement at the lower end of the shaft tapers downwardly and has a top portion which substantially equals and is in line with the aggregate cross-section of the blades when 40 folded, whereby the blades themselves have little or no work to do in penetrating the ground, as their supporting shaft is driven in, the way for the passage of the folded blades being prepared by said pilot. In 45 order that the pilot may readily cut its way into the ground, it is not only provided with a point at its lower end, but it is also provided with flattened sides sloping toward or converging in the point and with cutting 50 edges between. In the preferred form of the invention, the pilot is parallelogrammatic in cross-section with the diagonals unequal in length, whereby the pilot partakes of the nature of a blade, its earth penetrat- 55 ing and obstacle cutting qualities being thus improved.

The shaft of my improved anchor is preferably made of wrought iron, and is upset at its upper end there to make it preferably sufficiently thick to enable the formation of 60 a guy wire receiving eye which is defined by a frame of metal of substantially the thickness of the balance of the shaft. This eye and the frame defining it are elliptical, with the major axis in line with the axis 65 of the shaft, whereby the strength of the upper end of the shaft is not only not weakened, but is rather strengthened, so as not to be materially modified in shape by the 70 hammer blows.

I will explain my invention more fully by reference to the accompanying drawing, showing the preferred embodiment thereof, and in which Figure 1 is a longitudinal view with the blades folded, the shaft 75 being shown with an intermediate portion broken away because of lack of space; Fig. 2 is a longitudinal view illustrating the blades open; Fig. 3 is a view of the lower end of the structure as shown in Fig. 1; 80 Fig. 4 is a view of the lower end of the structure as it appears in Fig. 2; Fig. 5 is a sectional view on line 5—5 of Fig. 1; Fig. 6 is a sectional view on line 6—6 of Fig. 2; Fig. 7 is a sectional view on line 85 7—7 of Fig. 1; and Fig. 8 is a sectional view on line 8—8 of Fig. 1.

Like parts are indicated by similar characters of reference throughout the different figures.

The wrought iron anchor shaft 1 is upset at its lower end to form an earth penetrating pilot 2, which is in the form of an inverted pyramid that is parallelogrammatic in cross-section with diagonals, as viewed in 95 such cross-section, of unequal length. There is thus formed an arrow-shaped blade with four downwardly and inwardly sloping cutting edges 3, 3 and 4, 4 that merge at the point 5. The edges 4—4 are of especial service in cutting obstacles encountered in the 100 downward progress of the structure.

The inverted base 6 of the pilot 2 is adjacent a pivot pin 7 that passes through the shaft 1, and upon the projecting ends of 105 which the anchor blades 8 are pivotally supported. The shaft 1 is so much smaller than the pilot 2 that the blades may be folded against the shaft and then be within the area of the top of the pilot. These blades 110 constitute screw blades, being desirably so pitched as to unfold by the resistance of the

earth when the shaft is turned in one direction, and to rest upon said shaft when the direction of rotation is reversed while within the ground. The blades illustrated are 5 so designed as to require three revolutions of the shaft in one direction to unfold them, the blades being substantially at right angles to the shaft when unfolded, and substantially parallel therewith when folded. Thus 10 the anchor may readily be driven into the ground and is securely positioned when the blades are unfolded after the anchor has been driven to position. It is obvious that the blades may readily be folded at will, 15 when the anchor is not in position, in order to prepare the anchor for entry within the ground. The blades are flattened throughout their greater parts, these flattened portions being nearly but not quite parallel with 20 the longer diagonal of the base 6 of the pilot, one blade (when folded) projecting slightly beyond one end of such diagonal and the other blade slightly beyond the other end of the diagonal. To bring these two projecting portions of the blades, when folded, substantially into the plane that includes 25 the cutting edges 4, the pin 7 is disposed at a slight angle to the plane containing these cutting edges, whereby the cuts made 30 by the edges 4 may readily be continued by the portions of the folded blades extending beyond the edges 4. Except for these slightly projecting portions of the folded blades, a cross-section taken any 35 where through them (when folded) will be within the area or geometrical figure defining the base of the pilot, or an area closely approximating the same. The earth entering portions of the anchor, by reason of 40 the diagonal arrangement illustrated, is made narrower to facilitate the entry of the anchor into the ground. There is thus produced an earth anchor in which the blades thereof do not perform any large part in 45 the formation of the opening required to receive them. The upper end of the shaft is upset, whereafter a guy wire receiving eye 9 is there formed, this eye being defined by a

frame 10 of a thickness approximating that of the shaft proper. The eye is elliptical in 50 shape, as is the eye frame 10, the major axis of the eye and frame being substantially coincident with the axis of the shaft. The top 55 of the elliptical frame 10 is flattened, as indicated at 11, to afford a well-defined and substantial place for receiving the hammer blows, which cannot materially mar the shape of nor weaken the guy wire engaging end of the shaft.

While I have herein shown and particularly described the preferred embodiment of the invention, I do not wish to be limited to the precise features of construction shown, as changes may readily be made without departing from the spirit of my invention. 60 65

Having thus described my invention, I claim as new and desire to secure by Letters Patent the following:

An earth anchor including a shaft; two blades pivotally mounted upon the shaft to 70 fold against the shaft or to unfold to be angular thereto; and a downwardly tapering penetrating pilot on the lower end of the shaft beneath the blades and that is parallelogrammatic in cross section, with cross- 75 sectional diagonals of unequal length, the shape of the largest aggregate cross section of the blades folded approximating that of the inverted base of the pilot, the pivotal axis of the blades being angular with respect 80 to the longer one of the cross-section diagonals to bring cutting portions of the free ends of the blades, which project beyond this diagonal, substantially in the plane of said diagonal, the shaft being so much 85 smaller than the pilot that the blades may be folded against the shaft and then be substantially within the area of the top of the pilot.

In witness whereof I hereunto subscribe 90 my name this seventeenth day of August, A. D. 1914.

CHESTER R. PIEPER.
